HARRY W. SCHWARTZ, OF ELKHART, INDIANA, ASSIGNOR TO C. G. CONN, LTD., OF ELKHART, INDIANA, A CORPORATION OF INDIANA

DESIGN FOR A SAXOPHONE OR SIMILAR ARTICLE

Application filed February 4, 1930. Serial No. 34,405. Term of patent 7 years.

To all whom it may concern:

Be it known that I, HARRY W. SCHWARTZ, a citizen of the United States, residing in the city of Elkhart, county of Elkhart, Indiana, have invented a new, original, and ornamental Design for a Saxophone or Similar Article, of which the following is a specification, reference being had to the accompanying drawing, forming a part thereof.

I claim:

The ornamental design for a saxophone or similar article as shown.

HARRY W. SCHWARTZ.
